UNITED STATES PATENT OFFICE.

ATTILIO SEBASTIANI, OF PORTSMOUTH, OHIO, ASSIGNOR TO THE SELBY SHOE COMPANY, OF PORTSMOUTH, OHIO.

WOOD-HEEL-BREAST-FLAP LAYER.

Application filed April 17, 1924. Serial No. 707,056.

To all whom it may concern:

Be it known that I, ATTILIO SEBASTIANI, a citizen of Italy, and a resident of Portsmouth, in the county of Scioto and State of Ohio, have invented certain new and useful Improvements in Wood-Heel-Breast-Flap Layers, of which the following is a full, clear, and exact description.

Among the principal objects which the present invention has in view are; to provide a suitable construction of resilient band for laying and holding a wood heel breast flap in position on a heel while the adhesive or cement applied thereto is hardening; and to provide an efficient and inexpensive band for the above purpose, and one which will occupy a very small space when not in use.

Drawings.

Figure 1 is a side elevation of a shoe in position on a jack post, with the breast flap unattached to the breast of the heel;

Figure 2 is a perspective view of my improved wood heel breast flap laying band;

Figure 3 is a side elevation of a shoe on a jack post with the band portion of my device in position for holding the heel breast flap in position;

Figure 4 is a side elevation of a shoe on a jack post with the band portion of my device in position, and showing the strap portion of the device encircling the heel of the shoe, and

Figure 5 is a bottom view of a shoe with my improved device in operative position thereon, and showing more especially the means for holding the same in locked position.

Description.

In the forming of a complete shoe, a step in the process consists in making the rear portion of the sole, otherwise known as the heel breast flap adhere to the breast of the heel, and it is for this purpose that I have devised my improved breast flap laying band.

The device consists of a rubber or resilient

band 1, a portion of which is substantially wider than the remaining portion of the band, and is shown at 2. A strap portion 3 is attached to the band 1, and extends rearwardly therefrom, and is provided with a suitably reinforced bottom hole 4 adjacent its outer end. The strap 3 is also made of a resilient material, for purposes later to be described.

After the wood heel 5 is attached to the shoe 6, a suitable adhesive is applied to the flap 7, and the shoe is placed on a jack post 8, with the back of the heel towards the person working on the shoe. The flap 7 is then placed on the breast of the heel, and the flap holder or band 1, is placed thereon with the broad portion of the same in the breast, so that the strap 3 will extend on the left side of the shoe. The band is then stretched so that it will extend over the point at the top and back of the last, after which the band will be stretched and wrapped a time and a half around the heel, and is fastened by hooking the bottom hole 4 over the corner of the top lift of the heel at the right side thereof, as clearly illustrated in Figure 5 of the drawings.

The flap holder or band is then left in this position until the adhesive has thoroughly dried on the breast flap, and the same is securely held in place.

From the foregoing description, it will be apparent that I have devised a highly efficient flap holder, which will be quite inexpensive to manufacture, and which will be most simple to operate.

Many minor changes in detail of construction may be resorted to without departure from the spirit of the invention.

Claims.

1. A heel breast flap holder comprising a resilient band adapted to be positioned about the breast of a heel, a portion of said band being wider than the remaining portion thereof, a resilient strap formed on said band and extended rearwardly therefrom, said strap being provided adjacent its outer

end with a hole for attachment to the top lift of the heel, to hold the said band in position.

2. A heel breast flap holder comprising a resilient band adapted to be positioned about the breast of a heel, a portion of said band being wider than the remaining portion thereof, a resilient strap formed on said

band and extending rearwardly therefrom and adapted to be wrapped under tension about said heel, said strap being provided adjacent its outer end with a button hole for attachment to the top lift of the heel, to securely hold the holder in operative position.

ATTILIO SEBASTIANI.
